UNITED STATES PATENT OFFICE.

ALBERT J. LUNDE, OF SAN FRANCISCO, CALIFORNIA.

DESIGN FOR AN ARTICLE OF MANUFACTURE.

46,746.

Specification for Design.

Patented Dec. 8, 1914.

Application filed September 8, 1914. Serial No. 860,814. Term of patent 3½ years.

To all whom it may concern:

Be it known that I, ALBERT J. LUNDE, a citizen of the United States, residing in the city and county of San Francisco and State of California, have invented a new, original, and ornamental Design for an Article of Manufacture, of which the following is a specification, reference being had to the accompanying drawing, forming part thereof.

The figure is a plan view of my design to be applied to an article of manufacture.

I claim:

The ornamental design for an article of manufacture, as shown.

ALBERT J. LUNDE.

Witnesses:

JOHN H. HERRING,
W. W. HEALEY.
